SHEET STACKER

Daniel P. Glush and Julius A. Clauss, Detroit,
Mich., assignors to National Steel Corporation,
a corporation of Delaware

Application September 17, 1942, Serial No. 458,746

18 Claims. (Cl. 271—86)

1

This invention relates to sheet handling or piling apparatus, and more particularly to apparatus for stacking metal sheets or plates uniformly in a pile or stack as they are delivered from a sheet handling operation.

An important object of the present invention is to provide an apparatus for piling sheets and which is operative to pile sheets evenly with their lateral and end edges in vertical alignment so that the finished pile of sheets presents the appearance of a rectangular block having smooth and even faces. The ability of the apparatus to form a smooth and even pile of this character is of great utility when the piled sheets are to be subsequently annealed as the danger of burning the edges of projecting sheets during the annealing process, which is always present when the sheets are unevenly piled, is thereby eliminated.

Further objects of the invention are to provide a machine for piling sheets which is readily adjustable to accommodate sheets of different widths and lengths and which is of relatively simple construction and not liable to get out of order under conditions of use.

Further objects and advantages of the invention will become apparent as the following detailed description proceeds taken in conjunction with the accompanying drawings wherein:

Figure 1 is a plan view of a piling apparatus embodying our invention.

Figure 2 is a side elevation thereof.

Figure 3 is an end view of the piling apparatus looking in the direction opposite to the direction in which the sheets move from the slitting machine.

Figure 4 is a sectional view taken on the line 4—4 of Figure 1.

Figure 5 is a sectional view taken on the line 5—5 of Figure 1.

Referring to the drawings in detail and particularly to Figure 1, the sheet slitter (not shown) which may be of any conventional form is stationed at the left of and closely adjacent the piling apparatus generally designated by the numeral 10. The piling apparatus comprises a plurality of side frames 11, 12, 13 and 14 mounting a plurality of rollers 15 forming a roller type floor conveyor. As seen in Figures 1, 3 and 5, two sets of floor conveyors are provided, one set comprising frame members 11 and 12 together with a plurality of rollers 15 and the other set comprising frames 13 and 14 together with a plurality of rollers 15.

Adjacent the entrance side of the apparatus there is provided a supporting rod 16 suitably

2

supported in brackets 17 and 18. A pair of resilient members 19 are slidably and pivotally mounted by means of slidable hinge members 54 on rod 16 and a more detailed description of the construction and function of these resilient members will appear as the description of the apparatus proceeds.

Located between the two sets of floor conveyors and suitably supported thereabove is a rail or guide member 20 on which the margins of the sheet adjacent the slit edge are adapted to ride as the two sections of the slit sheet emerge from the slitter. The rail 20 is suitably supported at its forward end by a vertical supporting post 21 secured to a horizontal beam 22. At its other end rail 20 is supported by a bracket 25 which in turn is suitably supported on or adjacent the slitter. A pair of supporting rods 23 and 24 are mounted at each side of rail 20 and run substantially parallel therewith. Bracket 25 carries ears 26 supporting rods 23 and 24 at the entrance end of the apparatus and a pair of supporting members 27 and 28 resting on post 21 support the rods at the other end of the apparatus.

Resilient members 19 are slidably and pivotally mounted on rods 23 and 24 by means of slidable hinge members 55. A post 56 having a base member 57 is mounted on the upper flange of beam 22. Base member 57 carries a pair of spacer elements 58 slightly less in thickness than the upper flange of beam 22. By means of clamping strips 59 and bolts 60, post 56 is clamped in any desired position along beam 22. As best shown in Figures 2 and 5, post 56 carries an abutment member 61 on each side. Each resilient member 19 carries a pivoted pin 30 which enters a coil spring 31. Adjusting nuts 62 engage one end of the spring. The other end of spring 31 is connected to an abutment contact member 63. Pin 30 passes freely through contact member 63 and abutment member 61. Adjustment nuts 62' on this end of pin 30 hold spring 31 in compression. Thus movement of resilient member 19 toward post 56 is resisted by spring 31. Although Figure 5 is a section taken at 5—5 in Figure 1, this figure also constitutes an accurate showing looking at the opposite side of post 56.

Referring to Figure 2, a similar arrangement provides a limited resilient movement to each of plates 19. As seen in this figure, pin 32 is pivoted to the inner lower end of plate 19 and passes through bracket 33. Spring 34 provides the resiliency to plate 19.

A pair of side rigid abutment members 35 are suitably supported on each side of rail 20 as

clearly shown in Figure 1. The supporting framework for each pair of abutment members comprises a pair of cross bars 36 carried on the side frame members with a pair of longitudinal bars 37 adjustably mounted relative to the rail 20 on the cross bars by being welded or otherwise suitably fastened to plates 36'. The abutment members 35 are carried by the longitudinal bars 37 and by movement of these bars are adjustable to and from the rail 20. The abutment members are also movable relative to each other along bars 31. These adjustments are made possible by sliding and clamping connection of plates 36' with cross bars 36 and plates 39 with longitudinal bars 31. As indicated in Figure 1, such connection may be in the form of bolts carried by the plates and slidably received by the slots of the bars. As a result of this construction, the distance between abutment members 35 may be varied depending on the length of the slotted sheet sections or relative to the rail depending on the width. Each of the side abutment members comprises a vertical plate 38 pivotally connected to a horizontal plate 39 which in turn is secured to bars 37. A toggle brace 40 holds plate 38 in vertical position but is so constructed as to permit plate 38 to be folded into substantially horizontal position to enable the stack of plates to be readily removed.

Referring to Figure 3, the toggle brace 40 comprises upper and lower members 41 and 42 pivotally connected to each other at 43. Upper member 41 is pivotally connected to vertical plate 38 at 44 and lower member 42 is pivotally connected to horizontal plate 39 at 45. A stop 46 on an extended portion of member 42 contacts the upper surface of member 41 to limit the downward movement of the brace 40 and thereby hold the vertical plate in operative abutment position. Upward pressure against the pivoted members 41 and 42 will cause said members to fold on pivot point 43 and thereby collapse plate 38 into horizontal position against plate 39.

A further pair of abutment members 47 are provided forwardly of the side abutment members 35 to form the end of each stack. Each abutment member 47 comprises a vertical plate 48 pivotally connected to a bracing post 49. A toggle brace 50 constructed similar to toggle brace 40 is pivotally connected to plate 48 and post 49 and serves to hold plate 48 in operative abutment position. Inward movement of toggle brace 50 is limited by means of stop 51 which corresponds to stop 46. Movement of stop member 51 in a direction away from plate 48 will cause plate 48 to be swung out of abutment position when removal of the pile of plates is desired.

As will be apparent from an inspection of the drawings, the operation of the piling apparatus is as follows: The forward end of rail 20 lies directly adjacent the sheet slitter (not shown) and as the two slit sections of the sheet leave the slitter, the margins of the sheets adjacent the slit edge ride on the rail 20. When the sheet has passed completely past the shear, the two portions formed by the slit fall on each side of the rail. As seen in dotted lines in Figure 5, the pile of sheets indicated by the numeral 52 are stacked on skid 53 which rests on the rollers 15. The resilient plates 29 in conjunction with the side abutment members 35 form the sides of regular piles of the resulting sheets. The end abutment member 47 forms the forward edge of the pile and resilient plate 19 forces the sheets into abutment with member 47 to form the rear edge of

the pile. Thus the resilient members 29 and 19 cooperating with abutment members 35 and 47 form an even pile of sheets without any protruding edges in accordance with the primary object of the present invention. When it is desired to remove the stack of piled sheets, toggle braces 40 and 50 are operated to permit the plates 38 and 48 to be folded out of the way and the skids removed on the roller type floor conveyor. It is also apparent that abutment members 35 and 47 and resilient members 19 and 29 may be moved to any desired position to accommodate sheets of different sizes.

The curvature of resiliently mounted members 19 and 29 is such that each successive sheet is positively urged toward the abutment members no matter what the height of the stack may be. This requires that these members have some curvature throughout the dimension corresponding to the maximum desired height of a stack. This curvature is preferably such that only the last few sheets on the stack are contacted by the resilient members whereby they exert the maximum possible force on each new sheet fed to the stack. Considering Figure 5, it will be noted that the weight of the sheets being stacked acting on resilient member 29 forces this member to yield continually as the stack builds up. The slight curvature of resilient member 29 along the height of the stack results in an increasing degree of compression in spring 31 as the height of the stack increases. If the curvature of resilient member 29 is too great too much movement of spring 31 and its associated members will be necessary. Thus the optimum curvature is as flat as possible consistent with the above mentioned function of exerting maximum force on the descending sheet.

While the invention has been shown in the preferred form, it will be obvious to those skilled in the art that it is not so limited, but is susceptible of various changes and modifications, without departing from the spirit thereof, and it is desired therefore, that only such limitations shall be placed thereupon as are imposed by the prior art or as specifically set forth in the appended claims.

We claim:

1. A sheet stacker for receiving and stacking sheets having a plurality of straight edges comprising a guide member for supporting a sheet as it moves into the stacker, a support to receive the sheets in flat superposed position, abutment members adapted to contact a plurality of the edges of the sheet, curved members facing each abutment member pivotally mounted above the support and extending downwardly to a point adjacent the support, means acting on each curved member to urge the lower end of the same toward the facing abutment member, the curvature of a curved member being not substantially greater than that required to maintain the curved member in contact with the top sheet on the stack at all times during stacking.
2. A sheet stacking apparatus for receiving and stacking the slit sections of a sheet issuing from a slitter comprising a guide member arranged to support the slit sheet sections at the slit edges as the sections issue from the slitter and arranged to separate the slit sheet sections after the sections have completely passed the slitter, a support on each side of the guide member to receive the slit sheet sections in flat superposed position, resilient members arranged to contact two adjacent edges of each slit sheet section to exert a

force on each said edge, and an abutment member facing each resilient member and spaced therefrom a distance not greater than the corresponding dimension of the sheet section, the force exerted by each resilient member urging the sheet sections into engagement with the facing abutment member.

3. A sheet stacking apparatus for receiving and stacking in separate stacks the slit sections of a sheet issuing from a slitter comprising a guide member arranged to support the slit sheet sections at the slit edges as the sections issue from the slitter and arranged to separate the slit sheet sections toward separate stacks after the sections have completely passed the slitter, a stack support on each side of the guide member to receive the separated slit sheet sections in flat superposed position, resilient members arranged to contact two adjacent edges of each slit sheet section to exert a force on each said edge, one of the resilient members extending parallel to and adjacent the guide member, and an abutment member facing each resilient member and spaced therefrom a distance not greater than the corresponding dimension of the sheet section, the force exerted by each resilient member urging the sheet sections into engagement with the facing abutment member.

4. A sheet stacking apparatus for receiving and stacking in separate stacks the slit sections of a sheet issuing from a slitter comprising a guide member arranged to support the slit sheet sections at the slit edges as the sections issue from the slitter and arranged to separate the slit sheet sections toward separate stacks after the sections have issued from the slitter, a stack support on each side of the guide member to receive the separated slit sheet sections in flat superposed position, a resilient member arranged to contact an edge of each slit sheet section and extending parallel to and adjacent the guide member, a second resilient member arranged to contact a second edge of each slit sheet section and extending perpendicular to the guide member and adjacent the slitter, each resilient member being arranged to exert a force on the corresponding edge of the slit sheet section, and an abutment member facing each resilient member and spaced therefrom a distance not greater than the corresponding dimension of the sheet section, the force exerted by each resilient member urging the sheet sections into engagement with the facing abutment member.

5. A sheet stacker for receiving and stacking sheets having a plurality of straight edges comprising a guide member for supporting a sheet as it moves into the stacker, a support to receive the sheets in flat superposed position, abutment members adapted to contact two edges of the sheet, and resilient members in opposed position to the abutment members arranged to engage other edges of the sheet to exert a force urging said two edges of the sheet into contact with the abutment members, said force being so related to the weight of the sheets being stacked that a resilient member will yield under the influence of such weight while insuring said contact.

6. A sheet stacker for receiving and stacking sheets having a plurality of straight edges comprising a guide member for supporting a sheet as it moves into the stacker, a plane support below the guide member to support the sheets in flat superposed position, abutment members mounted on the support at a 90-degree angle thereto adapted to contact two edges of the sheet, and

resilient members in opposed position to the abutment members arranged to engage other edges of the sheet to exert a force urging said two edges of the sheet into contact with the abutment members, said force being so related to the weight of the sheets being stacked that a resilient member will yield under the influence of such weight while insuring said contact.

7. A sheet stacker for receiving and stacking sheets having a plurality of straight edges comprising a guide member for supporting a sheet as it moves into the stacker, a plane support below the guide member to support the sheets in flat superposed position, abutment members mounted on the support at a 90-degree angle thereto adapted to contact two edges of the sheet, means associated with the abutment members for folding the same away from the finished stack, and resilient members in opposed position to the abutment members arranged to engage other edges of the sheet to exert a force urging said two edges of the sheet into contact with the abutment members, said force being so related to the weight of the sheets being stacked that a resilient member will yield under the influence of such weight while insuring said contact.

8. A sheet stacker for receiving and stacking sheets having a plurality of straight edges comprising a guide member for supporting a sheet as it moves into the stacker, a plane support below the guide member to support the sheets in flat superposed position, abutment members mounted on the support at a 90-degree angle thereto adapted to contact two edges of the sheet, toggle means associated with the abutment members for folding the same away from the finished stack, and resilient members in opposed position to the abutment members arranged to engage other edges of the sheet to exert a force urging said two edges of the sheet into contact with the abutment members, said force being so related to the weight of the sheets being stacked that a resilient member will yield under the influence of such weight while insuring said contact.

9. A sheet stacker for receiving and stacking sheets having a plurality of straight edges comprising a guide member for supporting a sheet as it moves into the stacker, a plane support below the guide member to support the sheets in flat superposed position, abutment members mounted on the support at a 90-degree angle thereto adapted to contact two edges of the sheet, means for adjusting the position of an abutment member on the support with reference to the guide member, and resilient members in opposed position to the abutment members arranged to engage other edges of the sheet to exert a force urging said two edges of the sheet into contact with the abutment members, said force being so related to the weight of the sheets being stacked that a resilient member will yield under the influence of such weight while insuring said contact.

10. A sheet stacker for receiving and stacking sheets having a plurality of straight edges comprising a guide member for supporting a sheet as it moves into the stacker, a support to receive the sheets in flat superposed position, abutment members adapted to contact two edges of the sheet, and curved members in opposed position to the abutment members pivotally mounted above the support and extending downwardly to a point adjacent the support, means acting on each curved member to exert a force urging the lower end of the same toward an opposed abutment

member, said force being so related to the weight of the sheets being stacked that the lower end of a curved member will be moved away from an opposed abutment member under the influence of such weight while insuring contact of the stacked sheets with an opposed abutment member.

11. A sheet stacker for receiving and stacking sheets having a plurality of straight edges comprising a guide member for supporting a sheet as it moves into the stacker, a support to receive the sheets in flat superposed position, abutment members adapted to contact two edges of the sheet, curved members in opposed position to the abutment members pivotally mounted above the support and extending downwardly to a point adjacent the support, means acting on each curved member to exert a force urging the lower end of the same toward an opposed abutment member, said force being so related to the weight of the sheets being stacked that the lower end of a curved member will be moved away from an opposed abutment member under the influence of such weight while insuring contact of the stacked sheets with an opposed abutment member and means for adjusting the position of a curved member with respect to the guide member.

12. A sheet stacker for receiving and stacking sheets having a plurality of straight edges comprising a guide member for supporting a sheet as it moves into the stacker, a support to receive the sheets in flat superposed position, abutment members adapted to contact two edges of the sheet, means for adjusting the position of an abutment member on the support with reference to the guide member, curved members in opposed position to the abutment members pivotally mounted above the support and extending downwardly to a point adjacent the support, means acting on each curved member to exert a force urging the lower end of the same toward an opposed abutment member, said force being so related to the weight of the sheets being stacked that the lower end of a curved member will be moved away from an opposed abutment member under the influence of such weight while insuring contact of the stacked sheets with an opposed abutment member, and means for adjusting the position of a curved member with respect to the guide member.

13. A sheet stacker for receiving and stacking sheets having a plurality of straight edges comprising a guide member for supporting a sheet as it moves into the stacker, a support to receive the sheets in flat superposed position, abutment members adapted to contact two edges of the sheet, and convexly curved members in opposed position to the abutment members and extending from the neighborhood of the guide member downwardly to points adjacent the support, resilient means associated with each curved member to exert a force urging the lower end of the curved member toward the opposed abutment member, said force being so related to the weight of the sheets being stacked that the lower end of a curved member will be moved away from an opposed abutment member under the influence of such weight while insuring contact of the stacked sheets with an opposed abutment member.

14. A sheet stacker for receiving and stacking sheets having a plurality of straight edges comprising a guide member for supporting a sheet as it moves into the stacker, a support to receive the sheets in flat superposed position, abutment members adapted to contact two edges of the sheet, convexly curved members in opposed posi-

tion to the abutment members and extending from the neighborhood of the guide member downwardly to points adjacent the support, resilient means associated with each curved member to exert a force urging the lower end of the curved member toward the opposed abutment member, said force being so related to the weight of the sheets being stacked that the lower end of a curved member will be moved away from an opposed abutment member under the influence of such weight while insuring contact of the stacked sheets with an opposed abutment member, and the curvature of a curved member being sufficient to maintain the curved member in contact with the top sheet of the stack at all times during stacking.

15. A sheet stacking apparatus for receiving and stacking the slit sections of a sheet issuing from a slitter comprising a guide member arranged to support the sheet sections at the slit edges as the sections issue from the slitter, a support on each side of the guide member to receive the slit sheet sections in flat superposed position, a resilient member arranged to contact an edge of each slit sheet section and extending parallel to and adjacent the guide member, a second resilient member arranged to contact a second edge of each slit sheet section and extending perpendicular to the guide member and adjacent the slitter, each resilient member being arranged to exert a force on the corresponding edge of the slit sheet section, and an abutment member facing each resilient member and spaced therefrom a distance not greater than the corresponding dimension of the sheet section, said force being so related to the weight of the sheets being stacked that a resilient member will yield under the influence of such weight while insuring contact of the stacked sheets with the facing abutment member.

16. A sheet stacking apparatus for receiving and stacking the slit sections of a sheet issuing from a slitter comprising a guide member arranged to support the sheet sections at the slit edges as the sections issue from the slitter, a support on each side of the guide member to receive the slit sheet sections in flat superposed position, a resilient member arranged to contact an edge of each slit sheet section and extending parallel to and adjacent the guide member, a second resilient member arranged to contact a second edge of each slit sheet section and extending perpendicular to the guide member and adjacent the slitter, each resilient member being arranged to exert a force on the corresponding edge of the slit sheet section, means movably supporting the first resilient member for movement in a line parallel to the guide member, means movably supporting the second resilient member for movement in a line perpendicular to the guide member, and an abutment member facing each resilient member and spaced therefrom a distance not greater than the corresponding dimension of the sheet section, said force being so related to the weight of the sheets being stacked that a resilient member will yield under the influence of such weight while insuring contact of the stacked sheets with the facing abutment member.

17. A sheet stacking apparatus for receiving and stacking the slit sections of a sheet issuing from a slitter comprising a guide member arranged to support the sheet sections at the slit edges as the sections issue from the slitter, a support on each side of the guide member to receive the slit sheet sections in flat superposed

position, resilient members arranged to contact two adjacent edges of each slit sheet section to exert a force on each said edge, an abutment member facing each resilient member and spaced therefrom a distance not greater than the corresponding dimension of the sheet section, said force being so related to the weight of the sheets being stacked that a resilient member will yield under the influence of such weight while insuring contact of the stacked sheets with the facing abutment member, means movably supporting the abutment members for movement toward and away from the facing resilient members.

18. A sheet stacking apparatus for receiving and stacking the slit sections of a sheet issuing from a slitter comprising a guide member arranged to support the sheet sections at the slit edges as the sections issue from the slitter, a support on each side of the guide member to receive the slit sheet sections in flat superposed position, a first resilient member arranged to contact an edge of each slit sheet section and extending parallel to and adjacent the guide member, a second resilient member arranged to contact a second edge of each slit sheet section and 25

15 means movably supporting the first resilient member for movement in a line parallel to the guide member, means movably supporting the second resilient member for movement in a line perpendicular to the guide member, an abutment member facing each resilient member and spaced therefrom a distance not greater than the corresponding dimension of the sheet section, said force being so related to the weight of the sheets being stacked that a resilient member will yield under the influence of such weight while insuring contact of the stacked sheets with the facing abutment member, means movably supporting the abutment member facing the first resilient member for movement toward and away from the first resilient member and for movement along 20 a line parallel to the first resilient member, and means movably supporting the abutment member facing the second resilient member for movement toward and away from the second resilient member.

adjacent the slitter, each resilient member being arranged to exert a force on the corresponding edge of the slit sheet section, means movably supporting the first resilient member for movement in a line parallel to the guide member,

DANIEL P. GLUSH.
JULIUS A. CLAUSS.
